UNITED STATES PATENT OFFICE

ROGER K. LEE, OF HIGHLAND PARK, MICHIGAN

DESIGN FOR A RUBBER MATTING

Application filed November 22, 1930. Serial No. 37,756. Term of patent 14 years.

To all whom it may concern:

Be it known that I, ROGER K. LEE, a citizen of the United States, residing in the city of Highland Park, county of Wayne, and State of Michigan, have invented a new, original, and ornamental Design for a Rubber Matting, of which the following is a specification, reference being had to the accompanying drawings, forming a part thereof, in which—

Fig. 1 is a plan view of a piece of rubber matting showing my new design.

Fig. 2 is a fragmentary perspective view showing a transverse section of the mat taken on the line 2—2 of Fig. 1.

Fig. 3 is an enlarged view corresponding to Fig. 2.

I claim:

The ornamental design for a rubber matting substantially as shown.

ROGER K. LEE.
